METAL BENDING MACHINE

William E. Kane, Syracuse, N. Y.

Application March 23, 1935, Serial No. 12,639

27 Claims. (Cl. 153—61)

This invention relates to improvements in metal bending machines in which a plurality of forming rollers are adapted to have relative movement into and out of cooperative relation with each other.

Insofar as the applicant is aware, metal bending machines having forming rollers adapted to bend straight relatively stiff heavy metal articles such as strips of sheet iron, angle irons, T bars, channel bars or the like into circular form have been manually moved relatively to each other to bring them into cooperative relation to effect the forming operation and to bring them out of cooperative relation with each other to release the formed work from therebetween and after the formed work has been released by the forming rollers the work has been manually removed from between the rollers.

The main object of the present invention is to provide a metal bending machine of the above mentioned class with simple practical and efficient power means controlled by a slight physical effort for bringing the forming or bending rollers into and out of cooperative relation with each other and to automatically eject the formed work from between the rollers when said rollers are in inoperative relation with each other.

A more specific object of the invention is to provide the power means with safety means controlled by various moving parts of the mechanism whereby the movements of the power means for manipulating the rollers and ejecting the formed work must take place in predetermined sequential order so as to eliminate the possibility of a movement taking place out of order and thereby cause damage to the machine.

Another object of the invention resides in providing an adjustable feed table particularly adapted to be used in conjunction with my novel power control means.

In certain classes of work when the structure of the metal to be formed is particularly conducive to alteration in contour the same may be bent to the required formation by passing the metal but once between the forming rollers and in other cases it is often desirable and sometimes necessary to perform the bending operation by progressive stages and in so doing the material is passed between the bending rollers two or more times. In such cases the bending rollers are progressively moved toward each other during the bending operation until the work has reached the required form or contour.

Another object of the invention is to provide a metal bending apparatus with simple means

adapted to cooperate with the control means, for governing the position of the bending rollers relative to each other to progressively produce relative movement of the rollers toward each other, whereby the bending operation may be performed by a plurality of separate bending operations.

Other objects and advantages pertaining to the construction of the apparatus and to the form and relation of the parts thereof will more readily appear from the following description taken in connection with the accompanying drawings in which:

Figure 1 is a perspective view of a metal bending machine embodying the various features of this invention.

Figure 2 is a rear side elevation partly broken away and partly in section of the work ejector mechanism and the adjacent portion of the supporting frame or base.

Figure 3 is a detail transverse sectional view taken substantially in the plane of the line 3—3, Figure 2.

Figure 4 is a detail plan view of the forward or head end portion of the ejector mechanism and illustrating the same in operative relation with a safety control valve.

Figure 5 is a detail sectional view illustrating a modified form of ejector arm.

Figure 6 is a longitudinal vertical sectional view with portions of the base broken away and taken substantially in the plane of the line 6—6, Figure 9.

Figures 7 and 8 are detail vertical sectional views taken respectively on lines 7—7 and 8—8, Figure 6.

Figure 9 is a transverse vertical sectional view with portions thereof broken away, taken substantially in the plane of the line 9—9, Figure 6.

Figures 10 and 11 are detail sectional views taken respectively on lines 10—10 and 11—11, Figure 9.

Figure 12 is a side elevation of a portion of my novel roller control apparatus as viewed from line 12—12, Figure 6 with portions thereof broken away and in section.

Figure 13 is a diagrammatic view illustrating my novel power control apparatus and the associated parts of the metal bending machine.

Figure 14 is a diagrammatic view illustrating the bending rollers and the adjacent portion of the feed table in cooperative relation.

Figure 15 is a longitudinal sectional view through one of the automatic reversing valves.

Figure 16 is a diagrammatic view illustrating

an automatic control valve incorporated in the power line leading to the manually operated control valve.

There are several well known types of metal bending machines embodying rollers adapted to engage the metal and feed the same therebetween for bending the metal into circles or arcs thereof. The number of these bending rollers used and the relative arrangement thereof varies in different machines but in some instances, and particularly where pressure is applied at either end of the rollers, it is necessary to produce relative movement of the rollers toward and from each other to bring them from the cooperative position in close relation to each other for bending purposes into an inoperative position in more or less spaced relation to permit the removal of the finished work from the rollers.

In the machine selected to illustrate my invention, there are shown three such bending rollers, 1, 2 and 3, arranged in triangular formation and secured to respective horizontally disposed parallel shafts 4, 5 and 6, to be rotated thereby. The rollers 2 and 3 positioned at the base of the triangle are each smaller in this instance in diameter than the other roller 1 positioned above them at the apex of the triangle.

The shafts 5 and 6 for the lower rollers 2 and 3 are journaled in parallel spaced relation adjacent their ends in a pair of bearing brackets 8 mounted on a bed plate 9 adjacent respective ends of the rollers 2 and 3, said bed plate being mounted upon the upper end of a base 10 as shown in Figures 1, 6 and 9. The shafts 5 and 6 are driven in unison from a horizontally disposed drive shaft 12 journaled in the brackets 8 in a plane beneath the shafts 5 and 6 through the medium of gears 13, 14, and 15 secured respectively to the forward ends of the shafts 5, 6 and 12 as illustrated in Figures 6 and 8. The gears 13, 14 and 15 may, as shown, be mounted in a gear case 16 secured to the bed plate 9.

The drive shaft 12 has the rear end thereof extending some distance beyond the rearmost journal bracket 8 and has secured thereto a relatively large gear 18 which is in meshing engagement with a pinion 19 secured in any well known manner to a clutch shaft 20 which is disposed in a horizontal plane beneath the drive shaft 12 with one end thereof journaled in the base 10 and the other end journaled in a bracket 21 mounted on an extension 10' of the base 10.

The shaft 20 is driven from a motor 22 through the medium of a pair of sprocket gears 23 and 24 and a chain belt 25 and a clutch 26. One of the sprockets as 24 is secured by a key or otherwise to an extension or hub 27 provided on one of the clutch elements as 28 which in turn is rotatably mounted upon the clutch shaft 20. The other clutch element as 29 of the clutch 26 is splined to the shaft 20 as at 30 and is moved axially upon the shaft 20 into and out of frictional engagement with the clutch element 28 by a hand lever 31 pivotally connected at one end to the base 10 as at 32. The lever 31 is operatively connected with the clutch element 29 by a link 33 pivotally connected at one end to the lever 31 intermediate the ends thereof and a bifurcated arm 34 pivotally connected to the other end of the link and which is pivotally connected intermediate its ends to a fixed portion of the base and has the forked end thereof operatively engaging a peripheral flange 35 associated with the clutch element 29.

The bending roller 1 positioned at the apex of the triangle formation and which is commonly

known as the master roller is keyed or otherwise secured to the shaft 4 which in turn is journaled adjacent the rear end of the roller in the free end of a rock arm 37 which extends laterally from the shaft 4 toward the back side of the machine and is journaled upon a supporting shaft 38 mounted at its ends in blocks 39 which in turn are slidably mounted for vertical movement in slots 40 provided in vertically disposed brackets 41 mounted on the bed plate 9 as shown more particularly in Figures 1 and 9. The shaft 38 is disposed in substantially the horizontal plane of the shaft 4 when the roller 1 is in cooperative relation with the rollers 5 and 6 and the shaft 38 is adjustably maintained in this position by shims 42 mounted in the bracket slot 40 at either side of the block 39 so that if the master roller 1 is changed for another one of different diameter the supporting shaft 39 may be correspondingly raised or lowered to bring the same into the horizontal plane of the shaft 4 when said shaft is in the normal operative position.

The shaft 4 extends outwardly from the forward end of the roller 1 a relatively short distance and has rotatably mounted thereon a pressure roller 44 adapted to be engaged by a bearing block 45 secured to one side of a pressure head 46 as shown in Figures 1 and 6.

The pressure head 46 extends rearwardly in substantially a horizontal plane and is journaled upon the supporting shaft 38 at opposite sides of the arm 37. The pressure head is also provided with a bearing member 47 positioned at the opposite side thereof from the bearing block 45 and adapted to engage the upper surface of the arm 37 which is provided with a pair of axially spaced substantially flat horizontally disposed bearing surfaces 37' as shown in Figures 6 and 9.

The master roller 1 is rotated by the drive shaft 12 at substantially the same peripheral surface speed as the lower rollers 2 and 3 by a gear 49 mounted on the rear end of the shaft 4, a gear 50 mounted on the drive shaft 12 adjacent the rear face of the rear bracket 8 and an idler gear 51 mounted on a stud 52 secured in a boss 53 provided on the rear bracket 8 as shown in Figures 6 and 7. The idler gear 51 is rotatably mounted upon an eccentric bushing 54 which in turn is adjustably secured in the boss 53 in any suitable manner to permit said bushing to be rotated relatively to the boss whereby the gear 51 may be adjusted relatively to the gears 49 and 50.

The mechanism thus far described is of conventional construction and is operated in the usual manner to bend metal pieces into circles or arcs thereof; that is, the bending rollers 1, 2 and 3 are driven at the same peripheral surface speed by the motor 22 through the mechanism described including the manually controlled clutch 26. The lower rollers 2 and 3 are journaled on the bed plate 9 in fixed operative relation therewith and the upper or master roller 1 is journaled on the swinging arm or frame 31 for movement toward and from the lower rollers. The master roller is releasably maintained in predetermined relation to the lower rollers during the bending operation by the engagement of the pressure head or frame 46 with the pressure roller 44 and surfaces 37' of the arm 37.

The pressure head 46 has heretofore in the conventionally constructed machines been moved into and out of operative pressure engagement with the master roller 1 by manually controlled lever means which were connected with the

outer ends of laterally disposed arms 46' provided on the pressure head in spaced relation and said lever mechanism was releasably locked against upward movement to maintain the pressure head in operative relation with the master roll 4. Furthermore, when the pressure head 46 was moved upwardly out of operative engagement with the master roller the said roller was also moved upwardly a lesser distance but sufficiently to release the work engaged between the bending rollers and permit the same to be manually moved axially along the master roller and over the pressure roller 44 to make way for the next piece of work.

15 The mechanism shown in the drawings for moving the master roller into and out of co-operative relation with the lower rollers and for automatically ejecting the finished work from the master roller and which comprises the subject matter of this invention will now be described.

20

The bed plate 9 is provided in this instance with a pair of pendant lugs or bosses 56 arranged in longitudinal spaced relation near the front side 25 thereof as shown in Figures 6 and 9. A pair of supporting brackets 57 are arranged within the base 10 in longitudinal spaced relation and have their forward portions secured to a respective boss 56 and the rear portions secured to the rear 30 side of the bed plate by bolts or their equivalents. These brackets 57 extend some distance below the bed plate 9 in the plane of the rear portion thereof and have mounted therebetween a cylinder 35 59 which is pivotally connected adjacent the forward end thereof as by the trunnions 60 to the rear portion of said brackets; see Figure 9.

In the cylinder 59 is mounted for longitudinal reciprocated movement a piston 62 which has a piston rod 63 extending forwardly through a suitable stuffing box provided at 64 in the forward end plate 65 of the cylinder. The outer end of the piston rod 63 is positioned in the slot 66 provided in a rock frame 67 and is journaled upon a pin 68 which has the ends thereof mounted in the rock frame at opposite sides of said slot. The rock frame 67 extends some distance below the pin 68 and has the lower end thereof pivotally connected to the supporting brackets 57 by a shaft 69.

50 A pair of rock arms 70 is disposed in substantially a horizontal plane, one adjacent the outside of each of the supporting brackets 57 and said arms have the rear ends thereof pivotally connected to a respective bracket as at 71, Figure 9. The arms extend forwardly from the pivots 71 to within a relatively short distance of the forward side of the base 10 and are operatively connected with the piston rod 63 by means of a pair of toggle mechanisms 73.

60 Each of these toggle mechanisms comprises a pair of vertically disposed links 74 and 74', one of which has the upper end thereof pivotally connected as at 75 to pendant lugs 76 provided at the forward portion of the supporting bracket 57.

65 Each of the other links 74' has the lower end thereof pivotally connected as at 78 to a respective rock arm 76 a relatively short distance from the forward end of said rock arm and in substantially the vertical plane of the pivot 75. The inner adjacent ends of the links 74 and 74' of each pair are pivotally connected to each other and to a connecting link 79 by a pin 80. Each connecting link 79 extends rearwardly from the pivot 80 at a respective side of the rock frame 67 and has the 75 rear end thereof pivotally connected to a re-

spective end of the pin 68 upon which the connecting rod 63 is mounted.

It will thus be seen that the reciprocating movement of the piston 62 and piston rod 63 will produce a corresponding swinging movement of the rock frame 67 and will also produce rocking movements of the toggle mechanism 73 and arms 70 to move the outer or forward end of said arms upwardly and downwardly in a vertical plane. The forward movement of the piston 62 is limited by the engagement thereof with the forward end of the cylinder 59 while the rearward movement of said piston is limited by the engagement thereof with the rear end of the cylinder and in order to absorb some of the shock thereby produced, the cylinder is provided with annular buffer rings 83 composed of leather or similar material, positioned adjacent the inner face of the front and rear heads of the cylinder.

The relation of the piston 62, piston rod 63 and toggle mechanism to each other and to the cylinder 59, is such that when the piston is at the forward end of its stroke the toggle links 74 and 74' will be maintained in nearly a straight line with the pivot 80 positioned substantially in or a relatively short distance beyond the vertical plane passing through the pivots 75 and 78 as illustrated by full lines in Figure 9. In other words, when the piston 62 is at the forward end of its stroke the arms 70 will be maintained in their lowermost position with the toggle links 74 arranged slightly past dead center for locking said arms in said position against upward movement. When the piston 62 is moved rearwardly it is obvious that the toggle mechanisms will rock rearwardly about the pivots 75 while the frame will rock about the pivot 69 thereby producing an upward swinging movement of the connecting rod 63, lower links 74' and rock arms 70 until said members assume the positions illustrated by broken lines in Figure 9.

This vertical rocking movement of the arms 10 is utilized to produce a corresponding vertical rocking movement of the pressure head 46 and for this purpose the arms 10 are connected with the head 46 by means of a pair of connecting bars 85. These bars 85 extend upwardly from the interior of the base 10 through suitable apertures provided in the bed plate 9 and have their upper ends pivotally connected as at 86 to a respective arm 46' of the pressure head 46. The lower ends of the bars 85 are provided with a threaded rod 87 which extends through a vertically disposed slot 88 provided in the outer or forward end of a corresponding rock arm 10. Each rod 87 is adjustably secured to the corresponding rock arm 10 by nuts 89 screw threaded on said rod at either side of the rock arm.

It will now be understood that the vertical swinging movement of the head 46 produced by the arms 70 through the medium of the connecting bars 85 is sufficient to move the bearing block 45 and bearing member 47 a considerable distance above the pressure roller 44 and the bearing surfaces 37' on the arm 37 as shown by broken lines in Figure 9 and that when the head 46 is in the raised position the arm 37 together with the master roller 1 carried thereby is free to move upwardly to bring the roller out of cooperative relation with the lower rollers 2 and 3 for releasing the work contained therebetween.

The mechanism for raising the master roller and arm 37 comprises a pair of springs 92 75.

mounted on respective vertically disposed guide rods 93 which are supported at their lower ends in a bracket 94 secured to the rear bracket 8 beneath the arm 37. The rods 93 extend upwardly from the bracket 94 through respective apertures 95 provided in the arm 37 to a position some distance above the arm. The rods 93 have a free sliding movement in the arm apertures 95 to permit the necessary swinging movement of the arm. Each spring 92 is positioned between the arm 37 and a nut 96 screw threaded on the lower end of a respective rod 93 as shown in Figures 9 and 10. It will thus be seen that the springs 92 may be readily tensioned as desired by the manipulation of the nuts 96 and the nuts 96 may be secured in the adjusted position by any suitable means such as the lock nuts 97.

A stop bar 99 is provided for limiting the upward swinging movement of the arm 37. This stop bar is secured by a screw 100 at its lower end to a rearwardly extending lug 101 provided on the rearwardly positioned bracket 8. The upper end of the stop bar 99 is provided with a lateral extension or head 102 which extends over the adjacent portion of the arm 37 in spaced relation thereto when the arm is in its normal lowermost position. The stop bar 99 is preferably constructed with a definite length adapted to permit sufficient swinging movement of the arm 37 to free the work contained between the master roller 1 and the lower rollers 2 and 3 and at the same time maintain the drive gears 49 and 51 for the shaft 4 in meshing engagement and if it becomes necessary to alter the path of travel of the arm 37 due to a change in the diameter of the master roller and the drive gears therefor, the stop bar 99 is preferably replaced by another stop bar of required construction although it is obvious the one stop bar may be utilized for all working conditions by making the same adjustable.

The upward swinging movement of the arm 37 and master roller 1 is not only utilized to release the work but to also permit the passage of an ejector arm between the master roller and the lower rollers 2 and 3 for removing the finished work from between the rollers.

This ejector arm 104 as shown in Figures 3 and 4 comprises a relatively narrow arcuate portion 105 conforming somewhat to the contour of the master roller 1 and adapted to freely pass through the space between the master roller 1 and the lower rollers 2 and 3 when the master roller is in the raised or inoperative position. The other or outer end portion of the ejector arm is provided with a relatively large head portion 106 having opposed recesses 107 and 108 for slidably receiving respective horizontally disposed track bars 109 and 110. These track bars are arranged in parallel relation at the rear side of the bending rollers 1, 2 and 3 and are mounted in a pair of longitudinally spaced U-shaped brackets 111 secured to the bed plate 9. The ejector arm 104 is normally maintained at its innermost position with the portion 105 thereof extending over the lower rolls 2 and 3 and at the rear of the master roll 1 which as shown in Figure 6 is constructed slightly shorter than the lower rolls to provide a recess for the ejector arm.

The ejector arm 104 is reciprocated along the track bars 109 and 110 by a piston 112 mounted in a cylinder 113 which in turn is secured to a bracket 114 mounted on the base 10 at the forward end thereof as shown in Figure 1. The cylinder 113 like the cylinder 59 is provided with

buffer rings 115 at either end thereof adapted to be contacted by the piston 112 for limiting the movement of said piston in either direction.

The piston 112 is connected with the ejector head 106 by a piston rod 117 which extends outwardly through a stuffing box 118 provided in the forward end of the cylinder 113 and has the outer end thereof secured in any suitable manner to the ejector head. The travel of the piston 112 in the cylinder 113 is sufficient to bring the ejector arm from the normal innermost position at the rear of the master roller 1 to a position beyond the pressure roller 44 so as to move the work from the master roller 1 over the pressure roller 44 and deposit the same onto a chute 120 secured in any suitable manner to the forward end of the machine in operative alignment with the shaft 4 as clearly shown in Figures 1 and 6.

It will now be readily understood that the pressure head and ejector arm are both actuated through the medium of a respective piston mounted in a corresponding cylinder and it will be obvious that the pressure means for actuating the pistons may be a plus or minus pressure; that is, the pressure may be above or below atmospheric. Furthermore, I may utilize either a gaseous or a liquid substance as a pressure agent.

However, I preferably utilize air above atmospheric pressure for the pressure agent and the structure disclosed in the drawings is adapted to be so actuated.

In the system shown for supplying air under pressure to the cylinders 59 and 113, I preferably incorporate a manually operated control valve which may be actuated by a slight physical effort for effecting the commencement of the operation of the power means and three automatic control valves, one automatic safety valve for each cylinder and an automatic reversing valve for each cylinder. The manually operated control valve as 122 and the automatic control valves as 123, 124 and 125 are of the normally closed bleeder type and may be of any well known construction not believed to be herein necessary to illustrate or describe in detail. The safety valves 126 and 127 are also of well known construction and are adapted to normally remain in the closed position.

One of the automatic control valves as 123 is mounted adjacent the head operating cylinder 59 to be actuated at a predetermined position of the piston 62 for a purpose which will herein-after more fully appear. This valve as shown more clearly in Figure 12 is mounted on a bracket 135 secured to the base 10 beneath the cylinder 59. The stem 123' of the valve is arranged in the path of movement of rock arm 136 pivotally mounted at one end to the bracket 135 as at 137.

The arm extends rearwardly from this pivot 137 in substantially a horizontal plane with the rear end thereof positioned over the stem 123' and is yieldingly maintained in slightly spaced relation to said stem against a stop 139 by a spring 138 mounted upon guide pins with one end thereof in engagement with the arm and the other end engaging the bracket 135.

A slide bar 140 is mounted in the upper portion of the bracket 135 above the arm 136 and has one end thereof connected by a link 141 to a bracket 142 which in turn is secured to the rock frame 67. The other or rear end of the slide 140 is provided with a valve actuator which in this instance comprises a rock arm 143 pivotally connected intermediate its ends to the slide 140 as at 143'. The arm 143 is yieldingly maintained in

an upright vertical position against a shoulder 140' provided on the slide 140 by a spring 144 connected with the upper end of the arm and with the slide. The lower end of the arm extends 5 downwardly from the slide over the arm 136 for engagement with an inclined or cam surface 136' provided near the rear end of the arm for depressing said arm against the action of the spring 138 and thereby actuate the valve stem 123' 10 downwardly for opening the control valve 123.

Another one of the automatic control valves as 124 is mounted upon the bed plate 9 beneath the 15 ejector arm 104 when said arm is in the normal innermost position as shown more clearly in Figure 2. A rock arm 146 is mounted over the valve 20 124 and has one end thereof pivotally connected as at 147 to a bracket 148 which in turn is mounted on the bed plate 9. The arm 146 has the outer or free end thereof positioned over the valve 25 stem 124' of the valve 124 and normally maintained in slightly spaced relation thereto by a spring 149 mounted upon guide pins between the arm 146 and bed plate 9. A stop bar 150 secured to the bed plate 9 limits the upward movement of the arm 146.

A valve actuator in the form of a rock arm 152 is secured to the ejector head 106 as at 153 and is yieldingly maintained in a normally vertical position against a shoulder 154 provided on the head 106 by a spring 155 secured at one end 30 to the arm and at the other end to a rod 156 secured to the head. The lower end of the arm 152 is normally positioned a slight distance ahead of the free arm 146 and extends downwardly a 35 relatively short distance below the plane of the upper edge of said arm so that when the ejector is moved outwardly the actuator arm 152 will rock about the pivot 153 against the action of the spring 155 and pass over the arm 146 without depressing said arm against the action of the 40 spring 149. However, when the ejector arm is moved inwardly the actuator arm 152 engages an inclined or cam face 146' provided on the upper edge of arm 146 and depresses said arm 45 and the valve stem 124' for opening the valve 124.

The remaining automatic control valve as 125 as shown in Figure 2 is mounted in this instance upon the inner head 113' of the cylinder 113 and 50 has the valve stem 125' thereof positioned in the path of movement of a valve actuator 158 also mounted on the ejector head 106. This valve actuator 158 is in the form of a screw which is screw threaded in an upwardly extending projection 106' provided on the head 106 and is 55 locked in the adjusted position by a lock nut 159. The valve actuator 158 is so related to the valve 125 and the ejector head 106 that when the ejector is in its outermost position the actuator 158 60 will engage the stem 125' and open the valve 125.

One of the automatic safety valves as 126 is secured to a bracket 161 mounted on one of the supporting brackets 41 for the pressure head 46 with the stem 126' thereof in the path of movement of the head 46 to be engaged thereby when said head is in its uppermost position to effect the opening of the valve 126; see Figure 9.

The other automatic safety valve as 127 is mounted on a bracket 164 secured to the track 70 bar 110 adjacent the inner end thereof and as the valve stem 127' thereof positioned in the path of movement of a cam face 165 provided on the outer vertical face of the ejector head 106 as shown more clearly in Figures 2 and 4 so that 75 when the ejector is in its normal innermost po-

sition, the valve stem 127' will be depressed by the cam face 165 for maintaining the valve 127 in the open position.

The hereinbefore mentioned automatic reversing valves 128 and 129 may be constructed in any suitable manner and as shown more particularly in Figure 15, they are each of the sliding piston type and comprise a chambered case 167 having an inlet port 168, two supply ports 169 and an exhaust port 170 arranged in axially spaced relation in the body of the case. There is also provided a control port 171 in each head of the valve adapted to be connected to a respective control valve. The piston as 173 has a close sliding fit in the case 167 and is provided with an axially disposed channel 174 which is connected by a passage-way 175 with the inlet port 168. The channel 174 also is provided with a pair of axially spaced passages 176 adapted to alternately register with the supply ports 169 as the piston is moved from one extreme position in the case 167 to the other. The channel 174 of the piston is also connected with either end of the casing chamber 167' by relatively small bleed passages 178. The piston is also provided with a second channel 177 which is in permanent registration with the exhaust port 170 and is adapted to alternately engage with the supply ports 169 as the piston is moved longitudinally through the case 167. 30

Operation

By referring more particularly to Figure 13 it will be readily understood that the operation of my power control means for the bending machine is as follows:

The inlet ports 168 for each automatic reversing valve 128 and 129 are operatively connected with a suitable source of air under pressure such as a pressure pump, not shown, by means of an air conduit 180. The supply ports 169 of the reversing valve 129 are connected by conduits 181 and 182 with respective ends of the cylinder 59 while the supply ports 169 in the other reversing valve 128 are connected with respective ends 45 of the cylinder 113 by conduits 183 and 184. The conduit 182 for the reversing valve 129 has incorporated therein the safety valve 127 while the conduit 183 for the reversing valve 128 has incorporated therein the other safety valve 126. 50

One of the control ports 171 of the reversing valve 129 is connected by a conduit 186 with the manually operated control valve 122 and the other control port 171 of said reversing valve is connected by a conduit 187 to the automatic control valve 124. The reversing valve 128 has one control port 171 thereof connected to the automatic control valve 125 by a conduit 188 and the other control port of said valve is connected to the automatic control valve 123 by a conduit 189. 60

It will now be observed that when the machine is in the normal position with the pressure head 46 in the operative position for maintaining the master roller 1 in cooperative relation with the bending rollers 2 and 3 and with the ejector 65 104 at its normal innermost position all of the control valves 122, 123, 124, 125 and 126 will be in the closed position while the control valve 127 will be maintained in the open position by the engagement therewith of the ejector head 106 70 in the manner hereinbefore described.

After a piece of work has been passed between the master roller 1 and the lower bending rollers 2 and 3 to form the same in a circle or an arc thereof the pressure head 46 may be moved up- 75

wardly for releasing the master roll by a slight manual pressure upon the handle as 122' for the control valve 122 to open said valve. As the valve 122 is thus opened air from the end of the reversing valve 129 connected to the conduit 186 will escape through the valve 122 thereby permitting the pressure in the opposite end of the reversed valve 129 to move the piston 173 contained therein toward the conduit 186 thus connecting the conduit 182 with the supply conduit 180 through the channel 174. At the same time the conduit 181 leading from the outer end of the cylinder 59 will be connected with the atmosphere through the exhaust port 170.

15 Inasmuch as the valve 121 is maintained in the open position pressure from the conduit 180 will thus pass through the conduit 182 to the forward end of the cylinder 59 thereby causing the piston 62 contained in said cylinder to move to the opposite end of the cylinder. As the piston is thus moved through the cylinder the arms 70 will be rocked upwardly by the action of the toggle mechanism connecting said arms with the piston rod 63 thereby moving the pressure head 46 from the operative position shown by full lines in Figure 9 to the inoperative position indicated by broken lines in said figure.

30 As the piston 62 approaches the outer end of the cylinder 59 the valve actuator 143 will effect the opening of the control valve 123 so that the end of the reversing valve 128 connected with the conduit 189 will be connected with the atmosphere and the piston contained in said valve will be moved toward the conduit 189 thereby connecting the conduit 183 with the supply conduit 180.

35 It will now be observed that inasmuch as the head 46 is in the uppermost position the valve 126 will be maintained thereby in the open position and pressure will be supplied by the conduit 183 to the forward end of the ejector cylinder 113. The pressure thus applied to the ejector cylinder will move the piston therein to the rear end of said cylinder and thus cause the ejector 40 arm 104 to move outwardly and in so doing will engage the work positioned on the master roller 1 and eject the same from the machine onto the chute 120 or other suitable conveying means which may be associated with the machine.

45 50 During the initial movement of the ejector 104 the valve 127 will be permitted to close thereby shutting off communication of the forward end of the cylinder 59 with the supply conduit 180 and maintain a constant pressure within the cylinder 59 for maintaining the piston at the rear end of said cylinder and thus prevent the accidental inward movement of the piston. As the ejector 104 approaches the limit of its forward movement the valve actuator 158 will open the control 55 valve 125 and thereby connect the end of the throttle valve 128 associated with the conduit 188 with the atmosphere so that the piston contained in said valve will be moved toward the conduit 188 and will thereby connect the conduit 184 and the rear end of the cylinder 113 with the supply conduit 180 while the other conduit 183 and forward end of the cylinder 113 will be connected to the atmosphere.

60 65 70 The pressure thus reversed in the ejector cylinder 113 will cause the piston contained therein to move forwardly until the ejector 104 is again returned to its normal innermost position. As the ejector approaches its innermost position, the valve 127 will again be opened for operatively connecting the forward end of the cylinder 59 with the reversing valve 129. Also, the valve actuator 152 carried by the ejector will open the control valve 124 and thereby reverse the position of the piston contained in the reversing valve 129 which in turn will connect the rear end of the cylinder 59 with the supply conduit 180 so that the piston contained in the cylinder 59 will be moved forwardly and return the pressure head 46 to its lowermost operative position. As the head 46 is thus brought to the operative position, the valve 126 will be permitted to close, thus returning the mechanism to the original position and completing one cycle of operation of the power operating means.

15 It will be obvious that these cycles of operation may be repeated as often as desired by the operator simply opening the control valve 122. Furthermore, it will be observed that these successive movements of operation will be automatically produced and must be performed in predetermined order due to the co-action between the pressure head 46 and the control valve 126 and the ejector 104 with the control valves 124, 125 and 127.

20 25 In order that the speed of operation of the pistons 62 and 112 and the mechanism actuated thereby may be controlled, I preferably employ a plurality of metering valves 130 mounted in the conduits 181 and 182 and 131 mounted in the conduits 183 and 184.

30 35 Also, I preferably provide a manually operated control valve as 132 in the conduit 187 which together with the valve 122 enables the operation of the piston 62 and pressure head 46 to be manually controlled independently of the operation of the ejector operating means. I have illustrated at 133 a three-way valve adapted to be manually operated to close the supply conduit 180 leading to the throttle valve 128 and to connect said throttle valve with the atmosphere so that 40 the ejector may be entirely shut off from the fluid pressure when it is desired to operate the pressure head only.

45 50 When the pressure head 46 is to be operated independently of the ejector operating means, it will be understood that the closing of valve 133 will shut off the throttle valve 128, conduits 183, 184, 188 and 189 and the cylinder 113 from the source of pressure fluid and at the same time connect these elements with the atmosphere. The head 55 46 may then be power actuated for moving the same from the operative position to the inoperative position and vice-versa by the operator opening the valve 122 whereupon the piston in the throttle valve 129 will be actuated in the manner hereinbefore described to connect the conduit 182 and the forward end of the cylinder 59 with the fluid pressure and at the same time connect the rear end of the cylinder 59 and conduit 181 with the atmosphere, thereby permitting the unequal 60 pressure produced in the cylinder 59 to effect the inward movement of the piston 26 mounted therein, thus causing an upward rocking movement of the arm 70 to bring the head 46 to the raised position. When it is again desired to return the head 46 to its lowermost operative position, the valve 132 may be manually opened which will effect the movement of the piston in the throttle valve 129 and reverse the pressure in the cylinder 59 and thus cause the piston contained in said cylinder to move forwardly and restore the head 46 to its lowermost position in the manner hereinbefore described.

65 70 75 The work stock is fed to the rollers 1, 2 and 3 in predetermined relation therewith by the aid of

an adjustable table 192. This table comprises a supporting frame 193 which is slidably mounted for vertical movement in a U-shaped plate 194 secured by screws or other means to each of the bearing brackets 8. The frame 193 is maintained in operative relation with the plate by gibbs 195 secured to the outer face of the side members of the plate 194, as shown in Figures 1 and 9. The frame 193 is maintained in the adjusted vertical position by a screw 196 screw threaded in the lower portion of the frame with the end thereof engaging the adjacent portion of the bed plate 9. The screw 196 may be locked in the adjusted position by a lock nut 197.

To the upper face of the frame 193 is slidably mounted a base plate 198 which is clamped to the frame by the screw 199 which passes through an elongated slot provided in the base plate and is screw threaded in the frame 193. The inner end of the base plate 198 is provided with an upwardly extending lug 198' in which is mounted a pivotal shaft 200 which extends outwardly at both ends beyond the lug 198' and has rotatably mounted thereon a delivery chute 202. The delivery chute 202 is a channel member having the inner end thereof provided with pendant lugs 202' adapted to support the shaft 200 thereon.

The rear or outer end portion of the chute is provided with a pair of pendant spaced lugs 202" to which is rotatably connected a block 203 having a central opening in which is rotatably mounted the reduced end of a screw 204. The screw 204 extends downwardly from the block 203 and has the lower end portion thereof screw threaded in a block 205 which is rotatably connected at its ends to a pair of outwardly extending lugs 206 provided on the base plate 198. The lower end of the screw 204 is provided with a hand wheel 207 by which the screw may be manually manipulated. The chute 202 is also provided with a pair of stock guide plates 208. These plates are as shown in Figure 11, angular members which are adjustably secured to the bottom of the chute 202 by bolts 209 which pass through holes 210 provided in the chute. These holes 210 are arranged in transverse spaced relation to permit the guide plates to be adjusted toward and from each other for different widths of stock.

When setting the table 192 for feeding work stock of a predetermined size to the bending rollers 1, 2 and 3, the guide plates 208 are adjusted to extend normally to the axis of movement of the rollers and are spaced apart a distance substantially equal to the width of the work stock so as to permit a relatively close sliding fit of the stock therebetween; the chute 202 is adjusted vertically and horizontally by the manipulation of the screws 196 and 199 and the angular inclination of the chute is adjusted by the manipulation of the screw 204 so as to bring the chute in such a position that the work stock when resting flatly upon the chute 202 with the lower or inner end thereof engaging the adjacent roller 3, said stock will also contact with the master roller 1. It will thus be seen that the work stock has three points of contact, one at the inner end thereof where it engages the roller 3, two in spaced relation to said end where it engages the inner end of the chute 202 and three at an intermediate position where it contacts with the periphery of the roller 1. Furthermore, as soon as the bending rollers begin to draw the work stock inwardly therebetween, the bending operation of the stock will commence and will continue until the stock

has passed beyond the contact points between the rollers 1 and 3 so that a uniform curvature of the stock is produced throughout the entire length thereof and thereby eliminates the flat spots which often occur adjacent the ends of the stock and the separate operation necessary to either bend these flat portions to conform with the remainder of the work or to cut the same therefrom.

During the initial adjusting of the machine for operation upon a specific class of work, it is to be understood that the master roller 1 is adjusted relatively to the lower rollers 2 and 3, in such a manner that the points of tangency of said rollers will be spaced apart a distance substantially equal to the thickness of the work. Furthermore, during the adjustment of the table the lower end of said table is spaced from the adjacent portion of the periphery of the master roller 1 a distance at least greater than the thickness of the stock so that if the work is elongated slightly as it passes between the rollers 1, 2 and 3, due to the metal being of an exceptionally soft nature, and the forward end of the work is thereby brought into over-lapping relation with the rear end of the work before the work passes beyond the chute the work will not become jammed between the chute and the master roller 1.

It will now be understood, by referring to Figure 14, that as the rollers 1, 2 and 3 draw the work inwardly therebetween the work will be engaged at four points of contact to effect the bending thereof, one at *a*, the point of tangency between rollers 1 and 2, another at *b*, the point of tangency between rollers 1 and 3, another point at *c*, a position on the periphery of the roller, one intermediate the points *a* and *b*, and another point at *d*, the inner end edge of the chute 202. In order to prevent excessive wear of said chute the inner end thereof is preferably provided with a hardened wear plate 211. Furthermore, due to this pressure engagement of the work stock with the inner end of the chute the rear end of the stock as it passes beyond the inner end of the chute will produce a slight sound which is a signal for the operator that the bending operation is nearly completed and that he may then manipulate the valve 122 to commence the operation of the power means for ejecting the work from the machine.

When the work stock is of such a nature as to prevent the proper bending of the same by one passage thereof between the rollers 1, 2 and 3, I have provided a simple control means by which the stock may be again passed between the rollers without removing the stock from operative relation with the rollers. This means, as shown in Figure 9, comprises an adjustable stop block 212 which is slidably mounted in a guide head 213 secured to the bed plate 9 and the supporting brackets 51. The guide head 213 comprises a substantially flat surface 214 arranged in the path of movement of the upper end of the rock frame 67 and is inclined from the upper end thereof downwardly toward said frame.

The stop block 212 has a surface thereof inclined similarly to surface 214 so that when the block is moved downwardly along said surface the rear edge of the block will be brought into the path of movement of the upper end of the frame 67 and prevent said frame from moving to the normal foremost position of its stroke. In other words, when the stop block 212 is in its lowermost position, the rock frame 67 will be maintained thereby in an intermediate position slightly rear-

wardly of its foremost position so that the arms 10 will be maintained through the action of the toggle mechanism 73 in an intermediate position slightly above the lowermost position thereof and the heads 46 connected with said arms will also be maintained in a similar intermediate position and will permit the master roller 1 to be spaced a distance greater than the thickness of the material from the lower rollers 2 and 3 and thus produce only a partial bending of the work stock as said stock passes therebetween. As soon as the stock has completely passed between the rollers 1, 2 and 3 the block 212 is moved upwardly out of engagement with the rock frame 67 to permit said rock frame and the toggle mechanism 73 connected therewith to be moved forwardly to the normal operative position by the action of the pressure in the cylinder 59 upon the piston 62 and thereby bring the arms 70 and the head 46 20 to their lowermost operative position for maintaining the master roller 1 in the normal operative position relative to the rollers 2 and 3 to produce the final bending of the work.

The means for manipulating the stop block 25 212 in this instance comprises a lever 216 which is pivotally connected to the supporting brackets 57, by a pin 217 which passes through the lever a relatively short distance from the inner end thereof. The inner end of the lever is operatively connected with the stop block 212 by a link 218. The lever extends outwardly from the pivot 217 through a slot 219 provided in the base 10 and has the outer end thereof provided with a handle 220 by which the lever may be 30 manually manipulated. A spring 221 is connected with the inner end portion of the lever and with the guide head 213 as shown in Figure 9 for normally urging the stop block downwardly into its operative position. A stop screw as 222 associated with the bed plate 9 may as shown be utilized for limiting the upward movement of the stop block 212.

When it is desired to maintain the stop block 212 in its inoperative position out of the path of movement of the rock frame 67, this is readily accomplished by means of a pin 224 which is passed through a suitable opening provided in the lever outside the base 10 and into engagement with a bracket 225 secured to the adjacent portion of the base 10.

In Figure 5, I have shown a slightly modified form of ejector which comprise in providing the ejector head as 106' with a relatively short ejector arm 105'. This arm is adjustably secured to the head 106' by bolts and slots as indicated at 55 228 and is adapted to engage the work at one side of the master roller 1 to eject the same instead of beneath said roller as is the case with the ejector 104.

60 In Figure 16 I have illustrated an automatic control valve 230 which may be similar in construction to the automatic safety valve 126 in that it is of the normally closed bleeder type having a continuous passage therethrough. This valve is connected in the conduit 186 as shown by a branch conduit 186' in series with the manually operated control valve 122.

The control valve 230 may be positioned at any 70 convenient place adjacent the forming rollers 1, 2 and 3 and as shown in Figure 14 is arranged with the valve stem as 230' thereof adapted to be engaged by the rear end of the work as said end leaves the table 202 to automatically open said 75 valve and thereby effect the beginning of opera-

tion of the power control mechanism in the same manner as when the valve 122 is opened.

Although I have shown and particularly described the preferred embodiment of my invention I do not wish to be limited to the exact construction shown as various changes may readily be made both in the form and relation of the parts thereof without departing from the spirit of the invention as set forth in the appended claims.

I claim:

1. In a metal bending machine, cooperative rollers for feeding and bending said metal, pressure means for maintaining the rollers in cooperative relation, manually controlled power means associated with the pressure means for rendering the latter inoperative, means for automatically producing relative movement of the rollers to release the metal, and an additional power means controlled by the action of the first mentioned power means for automatically ejecting the released metal.

2. A metal bending machine, comprising in combination, cooperative rollers for feeding and bending said metal, a pressure head movable into and out of cooperative relation with the rollers 25 for maintaining said rollers in cooperative relation with each other, manually controlled power means for actuating the pressure head, and means for automatically ejecting the metal from the rollers when the pressure head is in the inoperative position.

3. In a metal bending machine, cooperative rollers for feeding and bending said metal, means for releasably maintaining the rollers in cooperative spaced relation, and additional means for 35 intermittently producing relative movement of the rollers toward each other to progressively reduce said spaced relation of the rollers during the bending operation.

4. In a metal bending machine, cooperative 40 rollers for feeding and bending said metal, power actuated means for releasably maintaining said rollers in cooperative spaced relation, and manually operated means cooperating with the power actuating means for progressively reducing said 45 spaced relation of the rollers during the bending operation.

5. In a metal bending machine, cooperative 50 rollers for feeding and bending said metal, a pressure head movable into cooperative relation with the rollers for releasably maintaining said rollers in cooperative spaced relation, power means controlled by a slight physical effort for actuating the pressure head, and manually operated means associated with the power means 55 for limiting the movement thereof whereby the spaced relation of the rollers may be altered during the bending operation.

6. In a metal bending machine, cooperative 60 rollers for feeding and bending said metal, power means for releasably maintaining the rollers in cooperative relation comprising a pressure head associated with the rollers, fluid pressure operating means connected with the head for moving the same from an inoperative position to an operative position in holding relation with the rollers, and manually operated means for controlling the operation of the fluid pressure means.

7. In a metal bending machine, cooperative 70 rollers for feeding and bending said metal, power means for releasably maintaining the rollers in cooperative relation comprising a pressure head associated with the rollers, fluid pressure operating means connected with the head for moving the same from an inoperative position to an op- 75

erative position in holding relation with the rollers, manually operated means for controlling the operation of the fluid pressure means, and means for automatically controlling the speed of operation of the fluid pressure operating means.

5 8. In a metal bending machine, cooperative rollers for feeding and bending said metal, power means for releasably maintaining the rollers in cooperative relation comprising a pressure head associated with the rollers, fluid pressure operating means connected with the head for moving the same into and out of cooperative relation with said rollers, means for automatically producing relative movement of the rollers when the head is in the inoperative position to release metal contained therebetween, and manually operated means for controlling the operation of the fluid pressure means.

10 9. In a metal bending machine, cooperative rollers for feeding and bending said metal, power means for releasably maintaining the rollers in cooperative relation comprising a pressure head associated with the rollers, fluid pressure operating means connected with the head for moving the same into and out of cooperative relation with said rollers, means for automatically producing relative movement of the rollers when the head is in the inoperative position to release metal contained therebetween, manually operated means for controlling the operation of the fluid pressure means, and a second power means controlled by a movable member of the first mentioned power means for automatically ejecting the metal from the rollers when said metal is released by the rollers.

15 10. In a metal bending machine, cooperative rollers for feeding and bending said metal, a holding member movable into and out of cooperative relation with the rollers, and power operating means connected with the holding member for actuating the same, said operating means including means for releasably locking said member against movement by pressure produced thereon by the rollers during the operation of said rollers.

20 11. In a metal bending machine, cooperative rollers for feeding and bending said metal, a holding member movable into and out of cooperative relation with the rollers for releasably maintaining said rollers in cooperative relation with each other, fluid pressure operating means, and means connecting the operating means with said holding member including a toggle mechanism adapted to releasably lock the holding member in operative relation with the rollers.

25 12. In a metal bending machine, cooperative rollers for feeding and bending said metal, roller holding means, fluid pressure operating means for moving the holding means into and out of cooperative relation with the rollers for releasably maintaining said rollers in cooperative relation with each other, an ejector member, a second fluid pressure operating means for actuating said ejector member to move the metal from the rollers, control means connected with the first mentioned fluid operating means and manually operated by a slight physical effort to effect the movement of the roller holding means out of cooperative relation with said rollers, a second control means connected with the second mentioned fluid pressure means and actuated at a predetermined position of the holding means for automatically effecting the operation of the ejector means, and a third control means connected with the first mentioned fluid pressure

30 operating means and actuated at a predetermined position of the ejector member for effecting the return of the holding means into operative relation with the rollers.

35 13. In a metal bending machine, cooperative rollers for feeding and bending said metal, a feed table mounted adjacent said rollers in cooperative relation therewith for bending the metal, and power means for producing relative movement of certain of the rollers and the remaining rollers and the table to release the bent metal, and means for automatically ejecting the released metal from operative relation with the rollers and table.

40 14. In a metal bending machine, cooperative rollers for feeding and bending said metal, pressure means for maintaining the rollers in cooperative relation with each other, power means associated with the pressure means for rendering the latter inoperative, and means for automatically producing relative movement of the rollers to release the metal.

45 15. In a metal bending machine, cooperative rollers for feeding and bending said metal, pressure means for maintaining the rollers in cooperative relation with each other, power means associated with the pressure means and controlled by the metal at a predetermined position of said metal for rendering the latter inoperative, and means for automatically producing relative movement of the rollers to release the metal.

50 16. In a metal bending machine, metal feeding and bending rollers, power means for rotating said rollers in unison, and separate power operated means set into operation by the metal at a predetermined position of said metal for automatically producing relative movement of said rollers to bring them out of cooperative relation with each other.

55 17. In a metal bending machine, metal feeding and bending rollers, power means for rotating said rollers in unison, and separate power operated means including a control element arranged in the path of the metal and set into operation by action of the metal thereon at a predetermined position of said metal for automatically producing relative movement of said rollers to bring them out of cooperative relation with each other and for ejecting the bent metal when said rollers are out of cooperative relation.

60 18. In a metal bending machine, metal feeding and bending rollers, a pressure head pivotally mounted at one side of the rollers for swinging movement into and out of cooperative relation with the rollers for releasably maintaining said rollers in cooperative relation with each other, power means for maintaining the head in cooperative relation with the rollers and adapted to be operated at a predetermined position of the metal for swinging said head out of cooperative relation with the rollers, and separate means set into operation as the head is moved to the inoperative position for producing relative movement of the rollers to release the metal.

65 19. In a metal bending machine, metal feeding and bending rollers, a pressure head pivotally mounted at one side of the rollers for swinging movement into and out of cooperative relation with the rollers for releasably maintaining said rollers in cooperative relation with each other, power means for maintaining the head in cooperative relation with the rollers and adapted to be actuated by the metal at a predetermined position thereof for swinging said head out of cooperative relation with the rollers, and sepa- 70

rate means set into operation as the head is moved to the inoperative position for producing relative movement of the rollers to release the metal.

- 5 20. In a metal bending machine, metal feeding and bending rollers, a pressure head pivotally mounted at one side of the rollers for swinging movement into and out of cooperative relation with the rollers for releasably maintaining 10 said rollers in cooperative relation with each other, power means for maintaining the head in cooperative relation with the rollers and adapted to be operated at a predetermined position of the metal for swinging said head out of cooperative 15 relation with the rollers, separate means set into operation as the head is moved to the inoperative position for producing relative movement of the rollers to release the metal, and means controlled by the head when said head is 20 out of cooperative relation with the rollers for ejecting the released metal.

21. In a metal bending machine having cooperative feeding and bending rollers arranged with the peripheral surfaces thereof in parallel 25 relation with each other, power means for rotating the rollers in unison, separate power operated means for producing relative movement of the rollers in directions substantially normal to said surfaces to bring them into and out of cooperative relation with each other, and a second 30 power operated means controlled by the action of the first mentioned power operated means when the rollers are in inoperative position for automatically moving the bent metal 35 longitudinally of the rollers to eject the same from said rollers.

22. In a metal bending machine having cooperative feeding and bending rollers arranged with the peripheral surfaces thereof in parallel 40 relation with each other, power means for rotating the rollers in unison, separate power operated means for producing relative movement of the rollers in directions substantially normal to said surfaces to bring them into and out of cooperative relation with each other, an ejector element 45 movable axially of the rollers and a second power operated means adapted to operate the ejector element when the rollers are in the inoperative position to discharge the bent metal 50 from said rollers.

23. In a metal bending machine having cooperative feeding and bending rollers arranged to rotate about parallel axes, a pressure element for maintaining the rollers in cooperative relation with each other, fluid pressure means in- 55

cluding a toggle mechanism for moving the pressure element into and out of operative relation with the rollers, and means for yieldingly urging the rollers in a direction to release the metal from therebetween. 5

24. A device as in claim 23 having additional fluid pressure operated means adapted to be controlled at a predetermined position of the pressure element for ejecting the bent metal from the rollers. 10

25. A device as in claim 8 having means for automatically controlling the speed of operation of the fluid pressure operated means.

26. In a metal bending machine, cooperative rollers for feeding and bending said metal, roller holding means, power operated means for moving the holding means in opposite directions to bring the same into and out of holding relation with the rollers for releasably maintaining said rollers in cooperative relation with each other, 15 an ejector member, a second power operated means for actuating the ejector member to move the metal from the rollers, control means connected with the first mentioned power operated means and manually operated by a slight physical effort to effect movement of the roller holding means in one of said directions, a second control means connected with the second mentioned power operated means and actuated at a predetermined position of the holding means for automatically effecting the operation of the 20 ejector means, and a third control means connected with the first mentioned power operated means and actuated at a predetermined position of the ejector member for effecting the movement of the holder means in the other one of said directions. 25

27. In a metal bending machine, in combination, metal feeding and bending rollers, power means for rotating said rollers in unison, separate power operated means for producing relative movement of the rollers to release the bent metal therebetween, additional power operated means including a fluid pressure operated mechanism for ejecting the released metal, control means including a manually operated member associated with one of said power operated means for effecting the operation thereof, and a second control means connected with the second power operated means and actuated at a predetermined position of the manually controlled power operated means for automatically effecting the operation of said second power operated means. 40 45 50

WILLIAM E. KANE. 55
